UNITED STATES PATENT OFFICE.

GEORGE H. PEMBROKE, OF NEW BRUNSWICK, NEW JERSEY, ASSIGNOR TO MARCUS H. HORTON, OF BROOKLYN, NEW YORK.

CHECK-PROTECTOR.

1,075,221.

Specification of Letters Patent.

Patented Oct. 7, 1913.

Application filed December 17, 1912. Serial No. 737,178.

To all whom it may concern:

Be it known that I, GEORGE H. PEMBROKE, a citizen of the United States, residing at New Brunswick, Middlesex county, in the State of New Jersey, have invented certain new and useful Improvements in Check-Protectors, of which the following is a full, clear, and exact specification.

My invention relates to improvements in check protectors and the same has for its object more particularly to provide an apparatus to imprint upon the check a statement in words and numerals indicating that the check upon which such statement is printed is not good for a sum in excess of the amount so indicated thereon.

Further said invention has for its object to provide an apparatus whereby one is enabled to print simultaneously upon both sides of the check a statement which will completely penetrate the check from both sides so that it will be impossible to remove the same without destroying the paper or material of the check.

Further said invention has for its object to provide an apparatus embodying a type roller, and an inking roller which is so arranged and supported relatively to said type roller that it serves as a means for holding the type roller to its adjusted position during the printing operation.

Further said invention has for its object to print upon the back of the check, but in reversed form, the same statement which is printed upon the face of the check.

To the attainment of the aforesaid objects and ends my invention consists in the novel details of construction and in the combination, connection and arrangement of parts hereinafter more fully described and then pointed out in the claims.

In the accompanying drawings wherein like numerals of reference indicate like parts:—Figure 1 is a side view, partly broken out, showing one form of apparatus constructed according to, and embodying my said invention; Fig. 2 is a section taken on the line 2—2 of Fig. 1 looking in the direction of the arrow; Fig. 3 is a detail transverse section taken on the line 3—3 of Fig. 2 showing the construction and arrangement of the type roller and the inking roller therefor; Fig. 4 is a front view of the apparatus; Fig. 5 is a detail, inverted plan view of the

head carrying the printing roller and related parts, and Fig. 6 is an inverted plan view of the base showing the construction and arrangement of the lower inking mechanism.

In said drawings 10 designates the apparatus as a whole comprising a hollow base 11 provided at its rear end with bearings 12, 12 in which is pivotally secured the rear end of a pivoted arm 13.

14 denotes a coil spring interposed between the underside of the arm 13 and the upper side of the base 11.

15 denotes a rod extending through the spring 14 and having its upper end secured to the arm 13, and its lower portion passed through the base 11, and its end turned over to form an angular member which engages the underside of said base whereby to limit the upward movement of the arm 13. Adjacent to the forward end of the base 13 are provided oppositely arranged inclined transverse guides 16, 16^a which are substantially coextensive in width with said base 11. Intermediate the inner opposing edges of the guides 16, 16^a is provided a shallow recess within which is disposed a bar 17 having a resilient face 18 of rubber, leather or the like secured upon its upper surface. The base 11, adjacent to the inner opposing edges of the guides 16, 16^a, is provided with two transverse parallel recesses to allow for the passage of an ink ribbon 19 whose opposite ends are secured to rollers 20, 20^a mounted in the base 11, and provided at their corresponding projecting ends with knurled heads 21, 21^a by means of which said ink ribbon may be wound from one roller to the other.

22 denotes an inclined guide plate secured along the front edge of the base which serves to guide the check into position upon the printing ribbon 19. At the forward end of the arm 13 is provided a hollow head 23 which is open at its underside, and within said hollow head 23 is disposed a printing roller 24 which is revolubly mounted upon a shaft 25 provided at one of its projecting ends with a knurled head 25^a, and an indicating dial 26 bearing characters which correspond with the parallel lines of the type arranged upon the printing roller 24. The printing roller 24 is composed of a core of wood or other suitable material 27, upon which is secured a type

plate 28 which is conformed to said roller 27. The said type plate bears upon its outer surface a series of parallel lines of type, each of which indicates that the 5 check is good for a sum not exceeding the particular amount specified in words and numerals. These words and numerals, for example, may begin with "Five" and end with "Ten thousand." 10 Upon the underside of the head are arranged two transverse bars 29, 29^a which have their ends secured to the opposite lower edges of the head 23 and are so arranged relatively to the printing roll 24 15 that only one of the lines of type can act upon a check when disposed below the head 23 and upon the portion of the inking ribbon 19 disposed over the support 17. 20 denotes an inking roller which is supported at its opposite ends in bearings 31, 31 carried by a plate 32 secured to the rear side of the head 23 by adjusting screws 33, 33. The upper edge of the plate is provided at its opposite ends with upwardly 25 extending projections 34, 34 from which extend inwardly projecting members 35, 35, which bear against the outer surface of the head 23. By adjusting the said screws 33 the plate 32 is caused to act as a spring 30 bearing by means of which the pressure with which the inking roller 30 is caused to bear against the type roller may be regulated so as to insure the proper inking of the type. The inking roller 30, by reason 35 of its spring adjustment and its disposition relative to the printing roller 24 is caused to fit into the interval between two adjoining lines of type on the printing roller 24, and thereby serves to hold said printing 40 roller to its adjusted position ready for printing when a line of type has been brought properly into position above the interval between the transverse guides 29, 29^a secured to the underside of the head 23. 45 Upon the base 11, to the rear of the transverse guides 16, 16^a is arranged an angular stop 36 which is adjustably supported upon said base by a screw 37 extending through said stop, and a longitudinal slot 38 in said 50 base which is provided upon its lower end with a nut 39. The said stop 36 serves to limit the inward movement of the check when inserted under the head 23 in order to cause the statement to be printed at the 55 proper place upon the check. To the upper surface of the head is centrally secured a head 40 by means of which the arm 13 and the parts carried thereby can be depressed in order to bring any line of type on the 60 roller 24 into engagement with the surface of the check in order to print a designation thereon.

The operation of the apparatus will be obvious from the foregoing description.

Having thus described my invention what

I claim and desire to secure by Letters Patent is:—

1. An apparatus of the character described comprising a base, a movable member mounted thereon, means for maintaining said movable member normally in an elevated position, an adjustable printing member mounted upon said movable member, inking means engaging said adjustable printing member and serving to hold the same to its adjusted position, a support upon said base below said printing member, and inking means disposed upon said support and co-operating with said printing member to print a legend or statement upon both sides of a check when said movable member is depressed, substantially as specified.

2. An apparatus of the character described comprising a base, a movable member mounted thereon, spring means for maintaining said movable member normally in an elevated position, a printing roller revolvably mounted in said movable member, an inking roller adjustably mounted in said movable member and engaging said printing roller, guides arranged upon the underside of said movable member below said printing roller, a support on said base below said printing roller, and inking means disposed upon said support and co-operating with said printing roller to print a legend or statement upon both sides of a check when said movable member is depressed, substantially as specified.

3. An apparatus of the character described comprising a base, an arm pivotally secured at one end to said base, spring means for maintaining said arm normally in an elevated position, a hollow head secured to the free end of said arm, a printing roller revolvably mounted in said head, indicating means carried by said head, an inking roller adjustably mounted in said head and engaging said printing roller, guides upon the underside of said head below said printing roller, a support arranged on said base below said printing roller, and inking means disposed upon said support and co-operating with said printing roller to print a legend or statement upon both sides of a check when said head is depressed, substantially as specified.

4. An apparatus of the character described comprising a base, an arm pivotally secured at one end to said base, spring means for maintaining said arm normally elevated, a hollow head carried by the free end of said arm, a shaft supported in said hollow head, a printing roller arranged within said hollow head and secured to said shaft, an indicating dial secured to said roller shaft without said head, means for rotating said printing roller and dial, a spring support secured to said head, an inking roller car-

ried by said spring support and engaging said printing roller, means for adjusting the tension with which said inking roller bears upon said printing roller, a pair of 5 longitudinal guides secured upon the underside of said head below the center of said printing roller, said base having a recess arranged therein opposite the interval between the longitudinal guides on the underside of 10 said head, a resilient support arranged in said recess, a pair of rollers mounted in said base, an inking ribbon having its opposite ends secured to said rollers and extending over said resilient support, and means for 15 actuating said rollers, substantially as specified.

5. An apparatus of the character described comprising a base, an arm pivotally secured at one end to said base spring, means 20 for maintaining said arm normally elevated, a hollow head carried by the free end of said arm, a shaft supported in said hollow head, a printing roller arranged within said hollow head and secured to said shaft, an indicating dial secured to said roller shaft without said head, means for rotating said printing roller and dial, a spring support secured to said head, an inking roller carried 25

by said spring support and engaging said printing roller, means for adjusting the tension with which said inking roller bears upon said printing roller, a pair of longitudinal guides secured upon the underside of said head below the center of said printing roller, said base having a recess arranged therein opposite the interval between the longitudinal guides on the underside of 30 said head, a removable bar disposed within said recess, a resilient face secured to the upper side of said bar, a pair of rollers 35 mounted in said base, means for actuating said rollers, an inking ribbon having its ends secured to said rollers and its intermediate portion extending over said removable bar, and an adjustable stop arranged upon said 40 base to the rear of said removable bar, substantially as specified.

Signed at the city of New York, in the county and State of New York, this 14th day of December, one thousand nine hundred 50 and twelve.

GEORGE H. PEMBROKE.
